UNITED STATES PATENT OFFICE.

WINTHROP L. JACOBS, OF EAST ORANGE, NEW JERSEY, ASSIGNOR TO THE LOWELL MANUFACTURING COMPANY, OF MASSACHUSETTS.

DESIGN FOR CARPET.

SPECIFICATION forming part of Design No. 24,980, dated December 10, 1895.

Application filed November 11, 1895. Serial No. 568,637. Term of patent 3½ years.

To all whom it may concern:

Be it known that I, WINTHROP L. JACOBS, a citizen of the United States, and a resident of East Orange, in the county of Essex and State of New Jersey, have invented a new and original Design for a Carpet and Border, of which the following is a specification.

This invention comprises two parts, namely: the design A for a carpet and the design B for a border; and I do hereby declare that the drawing accompanying this specification conveys to any one a clear understanding of the same and is sufficient to enable such person to use my invention.

The design A is characterized by a ground of lacework and large conventional fleur-de-lis-like figures.

The design B is characterized by a ground of lacework and large conventional fleur-de-lis-like figures with upwardly and outwardly projecting stemwork between the fleur-de-lis-like figures.

What I claim, and desire to secure by Letters Patent, is—

1. In a design for a carpet, the body A, substantially as shown.
2. In a design for a carpet, the border B, substantially as shown.
3. The design for a carpet, comprising the body A and the border B, substantially as shown.

In testimony whereof I have signed my name to this specification in the presence of two subscribing witnesses.

WINTHROP L. JACOBS.
